UNITED STATES PATENT OFFICE.

JOSEPH A. NONES, OF NEW YORK, N. Y., ASSIGNOR TO J. HUNGERFORD SMITH COMPANY, OF ROCHESTER, NEW YORK, A CORPORATION OF NEW YORK.

DESIGN FOR A SHOW-CASE.

43,887.

Specification for Design.

Patented Apr. 22, 1913.

Application filed January 2, 1912. Serial No. 669,106. Term of patent 7 years.

To all whom it may concern:

Be it known that I, JOSEPH A. NONES, a citizen of the United States, residing at New York city, in the county of New York and State of New York, have invented a new, original, and ornamental Design for Show-Cases, of which the accompanying drawing is a representation.

The figure is a perspective view of a show case, showing my new design.

I claim:

The ornamental design for a show case as shown.

JOSEPH A. NONES.

Witnesses:

JESSE G. M. BULLOWA,
KATE M. NONES.
